DOOR OPENER

Jens Erickson, Valley City, N. Dak., assignor of
one-half to Henry C. Bjerke, Valley City,
N. Dak.

Application May 27, 1943, Serial No. 488,732

3 Claims. (Cl. 254—130)

This invention relates to door openers and it consists in the constructions, arrangements and combinations herein described and claimed.

It is the cardinal object of the invention to provide portable strut structures which may be readily installed upon the door opening of a freight car or other structure and having vertically spaced notches for reception of a crow-bar or the like whereby the door may be elevated, and in such cases where the door is made up of separate boards nailed to the frame posts, the crow-bar may be used to elevate the boards separately in a manner to avoid splintering of the boards, the splinters being objectionable when mixed with the grain, or other bulk commodity.

More specifically, it is an object of the invention to provide a pair of upright strut members, each having a clamp means for securing the upright members to upright frame posts of a door, each upright member having notches for support of an elevating tool such as a crow-bar.

Additional objects, advantages and features of invention will be apparent from the following description, considered in conjunction with the accompanying drawing, wherein

Figure 1 is a perspective view of the left side of a door opening having my invention installed upon the upright of the frame.

Figure 2 is a perspective view of the device for the left side of a door opening.

Figure 3 is a similar view of the device for use upon the right side of the door opening.

Figure 4 is a cross section on the line 4—4 of Figure 2.

Figure 5 is a cross section on the line 5—5 of Figure 2.

Reference is first made to Figure 1 of the drawing, wherein there is shown an upright post 10 forming the left side of the door opening of a car or the like, the floor of which is indicated at 11. At the right side of the opening a similar post, not shown, is employed, which is conventional.

My opener is designated by the reference character 12, two of which are employed, one upon each of the uprights 10, and consists of an angle bar 13 of suitable height so as to fit within the door opening of the car.

The angle bars 13 are of identical construction except that they are constructed to fit the right and left uprights of a door opening. As shown, the angle bars or struts 13 are provided at their upper ends with a U-shaped clamp 14, the bright portion 15 of which rests flatly upon a flange 16 where it is riveted or otherwise secured.

The legs 17 of the clamp extend at right angles and in parallel relation, spaced apart so as to snugly fit upon the upright 10 of the door opening. At the lower end of the angle bars a supporting base 18 is fixed, being shown as an angular strap, one leg 19 of which is riveted or otherwise secured to the flange 16 on the opposite face to that upon which the clamp 14 is secured. The leg 20 extends at right angles to 10 the angle bar and lies flush with the lower end thereof, and is adapted to rest snugly upon the car floor, as clearly shown in Figure 1.

The flange 21 of the angle bars are extended inwardly of the door opening in opposed relation to each other, and opening upon their outer vertical edges there are formed notches 22 which function as fulcrum points, suitably spaced vertically of the angle bars. The spacing of the notches 22 may vary, and as here shown are arranged in vertically disposed pairs. The lower edge of each notch 22 is slightly recessed, as at 23, for accommodation of a crow-bar or the like. By recessing the notches liability of slippage of the crow-bar or other tool is avoided.

25 In use, the angle bars 12 are positioned upon the uprights 10 of respective sides of a door which will position the notches 22 in parallel relation with the boards 24 constituting the door or closure of the grain car. A crow-bar 25 is now 30 placed in a notch 22 substantially aligned with the abutting edges of a pair of the boards 24 and forced inwardly therebetween so as to position the end of the crow-bar beneath the uppermost board. A downward pressure on the crow-bar 35 will exert an upward movement of the board and the nails which were employed to secure the board in position will be drawn outwardly from the uprights 10. Each side is worked alternately so that an even movement of the board is attained. In the event that boards of varying widths are employed in forming the door or closure, the notches 22 may not be aligned with abutting edges of the boards, and in such event it will be possible to remove two or more boards 40 at one time, depending upon the location of the notches. This will be possible since a substantial leverage is inherent in the structure.

45 While I have shown and described my door opener specifically, this is by way of illustration only, and I consider as my own all such modifications in construction as fairly fall within the scope of the appended claims.

I claim:

50 1. A door opener comprising an upright strut member, said strut having a clamp adjacent its

upper end adapted to frictionally engage an upright forming a door-way, a base supporting foot on the strut, and said strut having vertically spaced fulcrum points, a lever cooperative with said fulcrum points adapted to engage a portion of a door-way for effecting an upward movement of said portion of the door, said fulcrum points having a recessed part preventing slippage of said lever.

2. A grain door opener comprising an upright strut member, said strut member having a U-shaped clamp adjacent its upper end adapted to frictionally engage an upright forming the door opening, a base supporting foot on the strut, said

strut including a flange extended in a plane parallel to the door opening, a plurality of notches being formed on said flange and spaced vertically thereof forming fulcrums, a lever cooperative with said fulcrums adapted to engage a board of the grain door mounted within the door opening, thereby effecting an upward movement of the board, upon downward movement of the lever.

3. The structure of claim 2 in which the lower edge of said notches are recessed, preventing slippage of said lever.

JENS ERICKSON.
